UNITED STATES PATENT OFFICE.

JACOB HENRY RADCLIFFE, OF OLDHAM, COUNTY OF LANCASTER,
ENGLAND.

APPARATUS FOR EXTINGUISHING FIRES, GIVING ALARMS, &c.

SPECIFICATION forming part of Letters Patent No. 408,325, dated August 6, 1889.

Application filed December 7, 1886. Serial No. 220,934. (No model.)

To all whom it may concern:

Be it known that I, JACOB HENRY RADCLIFFE, a subject of the Queen of Great Britain, residing at Oldham, in the county of Lancaster, England, have invented certain new and useful Improvements in Apparatus for Extinguishing Fires and Giving Alarms of Fires and Alarms of Extinguishing-Fluid being Wasted, Causing Damage, of which the following is a specification.

I attain the objects of my invention by mechanical, chemical, and electrical combinations illustrated by the annexed drawings and specification.

15 Figures 1 and 2 represent two views of a strong tinned iron vessel which I use for generating carbonic-acid gas in solution with water by means of sulphuric acid and bicarbonate of soda.

20 My invention is not in the vessel, but relates to the attachments for automatic or other action of a fire-extinguisher, electric fire-alarm, or alarm of accidentally wasting of water, causing damage.

25 Figs. 1 and 2 show, respectively, a side and front view of the apparatus complete. Fig. 3 is a longitudinal section through the acid-bottle and crusher. Figs. 4, 5, 6, 7, 8, 9, 10, 11, 12, 13, 14, 15, and 16 are detail views, to be 30 hereinafter referred to.

I attach handles H on the sides of the vessel as means to carry it.

On large machines I affix three feet G on the bottom hoop of the machine, so that it may be 35 fixed firmly to the floor.

I will now refer to and explain my attachments and annexed drawings.

In Fig. 1, A is a tube to convey the extinguishing-fluid from the vessel.

40 B is an iron rod fixed to the bottom hoop and to a plate C under tap L. This rod forms a guide for the suspended weights W, which weights are suspended by a wire K, fixed to the wall or any other required place at one end of wire. On this wire I affix one or more links or couplings made of an alloy of metal, the fusing of which metal is accomplished by a low temperature. For this purpose I use tin, two parts; lead, three parts, and bismuth, five parts, 45 by weight. I place these links about ten feet

apart by wire lengths and make a coupling by fixing each end of the wire on the link, so that, the link being fused, the wire is parted and the weight W falls and pulls the chain and wheel around, thereby splitting the neck of 55 the acid-bottle at R, (see Fig. 3,) which causes a combination of the sulphuric acid and solution of salts and water, also letting a hinged electric switch fall, thus connecting the wires and completing the electric currents to ring 60 an alarm-bell.

Figs. 11, 12, and 13 represent three different views of the electric switch referred to.

In Fig. 1 the chain D is attached to weight W, passing over pulley E, hanging loosely at 65 D, passing round and hooked on the wheel in the manner shown in Fig. 14, so that when the wheel is turned by the falling weights the chain detaches itself from the wheel and lets the weights drop to the ground, when the 70 spring C, Fig. 3, on the spindle will recoil and close a valve at the bottom of the spindle S E, Fig. 3, and the spindle will recoil and close the valve again, that has been opened by the rotation of spindle by the falling weights. 75

The manner in which the chain rotates the spindle is shown at Fig. 7, Sheet 3, and this figure denotes the configuration of the wheel fixed on top of the spindle, Fig. 2, Sheet 1.

O represents the electric wires to convey 80 alarms, and which are affixed to the water-tube at F, Fig. 1, by means of a wood clip, which forms part of the electric switch, made as shown in Figs. 11, 12, and 13. The electric wires are fixed to the projecting ends of 85 copper wire X and Y, this wire being part of the hinge for completing the electric current to ring an alarm-bell.

I use an ordinary Leclanché battery to generate the necessary current of electricity to 90 ring the alarm-bell.

On the top of the vessel shown in Fig. 1 I place a screwed cap F (made in the manner shown in Fig. 3) for the purpose of charging or placing therein a bottle containing sulphuric acid, and by automatic action or otherwise split the bottle-neck of acid-bottle. I thereby bring about a combination of acid and solution of salts and water, generating carbonic-acid gas under great pressure to dis- 95 100

charge the contents of the machine. The acid is retained by a ground-glass stopper, which, together with the bottle-neck, is ground, thereby confining the acid within the 5 bottle until the latter is broken.

When the fire-extinguisher is required, I combine the acid with the salts and water by splitting the bottle-neck open at R (shown in Fig. 3) by pressure acting at the end of glass 10 stopper J or by forcing the bottle downward with the quick-threaded spindle shown in Fig. 1. The stopper in the bottle-neck, when inverted, rests on the set-pin P. The act of turning the spindle by handle or wheel there- 15 by splits the bottle-neck.

On the tube A, I fix a swivel with projecting arms, with or without a tap, for the distribution of the extinguishing-fluid in a circular form.

20 Figs. 15 and 16 show a sectional and side view, respectively, of this tap and swivel combined. When I use this tap and swivel, this tap is kept constantly open and the other tap shut; but in case the circular spray is not required, and the jet is required to direct the extinguishing-fluid, I close the upper tap and open the other tap and use the pipe and jet for extinguishing purposes.

Fig. 3 is a sectional view of the screw-cap 30 and acid-bottle attachments. The spindle has four threads upon it to work in screw-cap, and is provided with a spring C and a handle or wheel B. Underneath the screw-cap an acid-bottle case is fixed, and on this case I fix three 35 steel straps, one of which has a ring turned on it at O. This ring incloses part of acid-case cover, Fig. 3, at the outer edge of one of the square holes, forming a hinge with acid-cover, so that it can be turned back to take 40 out the bottle. The other two straps are fixed and have hooks turned on them, as shown at O''. The adjustable set-pin P may be screwed against the stopper of the bottle to hold it firm when the spindle is turned. When the 45 machine is charged, this screw-cap and acid-bottle are screwed into the top of the vessel, Fig. 1, and the chain D is passed over the wheel, as shown. The action of the end of the spindle against the bottle-bottom presses bot- 50 the down, and the adjustable set-screw acts against the bottle-stopper, thereby splitting the neck of bottle. On the top of tube A, I affix a circular sprinkler. On the top of the spindle of the screw-cap I place a wheel, as 55 shown (one-fourth size) in Fig. 14. On this wheel the chain is hooked and attached to weight W for automatic action when a coupling is fused. At top of the screw-cap, Fig. 3, I put a hole through cap part D' and also 60 through the spindle. This is to pass a wire 65 through to lock the spindle during the charging operation.

Fig. 5 is a plan of cast-metal acid-case cover, through which the adjustable set-pin P passes 65 at the center. Said cover is provided with

three square holes at right angles to each other.

The acid-bottle, Fig. 3, is shown broken at M M. This is to show that bottles may be made to any length for various sizes of ma- 70 chines.

Fig. 14 is a view of water-pipe C, with a tap and wheel d, weight E, chain F, fusible coupling B, and electric switch A attached. The pipe is for supplying extinguishing-fluid to 75 sprinkler.

Figs. 11, 12, and 13 are parts of my electric switch for automatic alarms. Fig. 11 is top view. Said swivel is made of wood. a is a hole in the center to embrace the tube, as 80 shown in Fig. 1 at F. This wood I cut in two parts, as lines indicate. On this I form a hinge and have copper wires projecting, as at X and Y. The switch is provided with three copper pieces, two of which I fix with 85 screws, as shown. The third is hinged on the copper wire X, and when connected rests on copper wire C, which projects, as at A. The electric wires are connected at these points X and Y. This wood block upon which the 90 electric switch is formed is screwed together, as shown in Fig. 11, and this is fixed on tube A. (See Fig. 1.) The movable part e of the hinge is held up by the weights W, and when they fall the part e falls also and rests on the 95 opposite wire, thereby completing electric circuit.

Fig. 9 is a cast-metal plate for attaching weights to pipe A and guide B. c is a hole in plate to slide on iron pipe; also d is a hole 100 to slide on iron rod.

Fig. 15 shows swivel and pipes. They may be made any length and have small holes in pipes ll. The liquid passing out at the holes 105 at opposite sides causes them to revolve and distribute the fluid.

Having now described and explained my invention for fire-extinguishing and alarms of fire, I claim—

In a chemical fire-extinguisher, the combination, with a receptacle adapted to contain a chemical solution and provided with a screw-threaded aperture and a valve-seat at the inner end thereof, of a glass vessel adapted to contain an acid and inverted in said receptacle, a crusher provided with a screw-threaded spindle engaging said aperture and a valve engaging said valve-seat, a spring applied to said spindle so that its resilience will tend to rotate it in a direction to close 115 the valve, a wheel on the spindle, a weight suspended by a fusible support, and a chain detachably connected at one end to the wheel and at the other end to the weight, substantially as described.

JACOB HENRY RADCLIFFE.
